JACOB HUFF, OF YOUNG AMERICA, ILLINOIS.

Letters Patent No. 86,160, dated January 26, 1869.

IMPROVEMENT IN CULTIVATORS.

The Schedule referred to in these Letters Patent and making part of the same.

To all whom it may concern:

Be it known that I, JACOB HUFF, of Young America, in the county of Warren, and State of Illinois, have invented certain new and useful Improvements in Cultivators; and I do hereby declare that the following is a full, clear, and exact description of the same, reference being had to the accompanying drawings, making a portion of this specification, in which—

Figure 1 is a perspective view of my invention.

Similar letters of reference indicate corresponding parts.

The nature of this invention relates to a cultivator of that kind called "walking-cultivator;" and

The invention consists in the peculiar arrangement for adjusting the distance of the plows apart; also, in the combination of parts forming the frame, and attaching the hitching-device in such way thereto that the proper line of draught may be preserved from the horse's hames to the front end of the plow-beams.

It also consists in a novel way of attaching the plows to the main frame, so as to allow free lateral and vertical movement of said plows.

To enable others to understand the construction and operation of my invention; I will proceed to describe it with reference to the drawings.

Letter A represents a curved or bowed axle, strengthened by the piece B, on its highest point.

Letter E represents the draught-pole, attached to the axle A, in the centre, and braced by the rods C.

D represents flat bars, of wrought-iron, attached to the axle A, at their upper end, and curved outward, and passing through the axle A at the lower end, and provided with nut i.

S represents a plate, carrying the wheel-spindles F, and having slots, V V, through which the bolt T and bar D' pass, for securing it to the main frame, and al-

lowing vertical adjustment of the frame, and consequently of the plow-beams.

L is a part of the joint or coupling, for attaching the plows to the main frame, and contains a slot through its centre, which slides on the bar D', allowing lateral adjustment of the plows, and being held at any desired point by the thumb-screw P.

m represents a bearing-plate, pivoted or jointed to plate L, by the bolt t, on which vertical movement of the plows is obtained.

J represents the beam-plates, attached to the end of the beams, and extending out far enough to receive the bearing-plates m, which are pivoted to them by a vertical bolt, n, allowing lateral movement of the plows.

W represents hooks, which are pivoted to the front end of plates L, and connect forward with the draught-bow X.

X represents a draught-bow, connected to the under side of the tongue E, arched and extending downward, with the ends horizontal, and to which are pivoted the bars Z, which connect at the upper end, by means of hooks g, with the double-tree.

The single-trees are attached to hooks, a, with series of holes, e e, whereby the draught is kept in a line from the horse's shoulders to the plow-beams; at the same time, so connected with the double-tree that unevenness of motion in the draught-animals will not be transmitted to the plows.

What I claim as new, and desire to secure by Letters Patent, is—

The combination of the axle A with support B, the slide S, braces C, and tongue E, substantially as described, and for the purpose set forth.
